UNITED STATES PATENT OFFICE.

CHARLES W. ALLEN, OF CHADRON, NEBRASKA.

STOCK-CAR.

SPECIFICATION forming part of Letters Patent No. 469,829, dated March 1, 1892.

Application filed March 28, 1891. Serial No. 386,799. (No model.)

To all whom it may concern:

Be it known that I, CHARLES W. ALLEN, of Chadron, county of Dawes, State of Nebraska, have invented certain new and useful Improvements in Stock-Cars, of which the following is a full, clear, and exact description.

My invention relates to improvements in vestibuled stock-cars, and has for its object to provide a means whereby when a train of 10 cars is to be loaded or unloaded it may be made a vestibuled one, through which the stock may be driven from one car to the other.

Another object of this invention is to provide partitions capable of being conveniently and expeditiously set up or removed to form the interior of the car into a single compartment or to divide it into a number of compartments.

20 A further object of the invention is to provide a means for watering the stock, whereby water may be supplied simultaneously to all the cars of the train, and also to provide a loft for hay or other feed, which will be effectively protected from the sparks of the locomotive.

In this invention the novelty consists in the construction, combination, and arrangement of the parts of the same, as will be hereinafter more fully set forth, and particularly pointed out in the claims.

Reference is to be had to the accompanying drawings, forming a part of this specification, in which similar figures and letters of reference indicate corresponding parts of the invention.

Figure 1 is a view in perspective of a pair of my improved cars vestibuled together. Fig. 2 is a side elevation of a car constructed in accordance with my invention. Fig. 3 is a plan view of the same, the roof being broken away. Fig. 4 is a perspective view of one end of one of the cars. Fig. 5 is a vertical section through the cars, showing one of the partitions.

45 The car is closed at each end by two gates 10 and 11, held in two corner-posts 12 and in crossways laid upon the floor of the car. The corner-posts 12 are fastened to the car by hinges in such a manner that they may be 50 swung across the end of the car at right angles to its sides or parallel to the side, as desired.

As shown in the drawings, they are pivoted in the roof and floor of the car-frame.

The side of the car is preferably constructed of suitable framing A, slatting 15, secured to the framing, and clapboarding 16, the latter of metal or the equivalent thereof, immediately below the eaves of the roof 17. The end gates are also preferably constructed of proper suitable framing and slatting secured thereon, 60 and are adapted to close across the center posts 18, which extend from the floor to the roof or any other overhead convenient support.

Within the car any desired number of center posts or pillars 19 are located, the same supporting a water-supply pipe 20, which extends from end to end of the car and out through ends. The flexible tube 21 is adapted to be connected to each end of the water-

tube 20. In a central portion of the roof, near one end, a tank 22 of any approved construction is erected, and the tank is connected with the pipe 20 by a branch pipe 23, provided with a suitable valve 24, whereby the supply 75 of water may be regulated at will. The top of the tank is preferably hinged so that it may follow the position of the running-boards 25. Two cross or transverse partitions 26 are adapted to slide against opposite sides of each 80 center post or pillar 19. The said partitions are slatted or formed of end pieces or cleats a and cross-bars, and the slats of the partitions preferably pass through the spaces between the slats forming a portion of the sides 85 of the car, as shown in Fig. 5. The lower ends of the cleats or side pieces a of the partitions move in grooves or ways a' in the floor of the car, whereby they are secured from lateral movement. Thus the partitions may be 90 drawn outward, so as to form the interior of the car into a single chamber or compartment, or they may be pushed inward and engaged with the pillars 19, thus dividing the car into a series of compartments, and when the partitions are in the last position (shown in Fig.

5) they are so held through the medium of the cleats a and hasps 27 or their equivalents, and the partitions, when held by such hasps, engaged in suitable staples 28. (Shown in Fig. 100 2.) The said staples are fastened with locks of any suitable description.

Within the car at each side one or more troughs 29 are located, the said troughs being preferably hinged to the sides, as shown in Fig. 5, and are supported in a horizontal position through the medium of hooks 30 or the equivalent thereof, the said hooks being provided with connections to the sides of the car, as is best shown in Fig. 4. By this means the troughs may be emptied by disengaging them from the hooks 30 and yet remain attached to the car. The troughs 29 are supplied with water through the medium of branch pipes 31, which connect at their upper ends with the central supply 20 to the lower end of the branch pipe extending down within the trough.

A series of eaves-trusses 33 is located beneath the roof 17, being attached at their ends to the sides of the car at the close boarding 20 16 and supported at their center by the main supply-pipe 20 or a ridge-beam supported by the posts 19. A space B intervenes between the series of truss-beams 23 and the roof, which space constitutes a loft for the reception of hay or other feed, and the trusses formed of beams are ranged near enough together to prevent the contents of the loft from falling to the floor of the car. The loft is reached through the medium of a door 34, located in the roof and having, preferably, hinged connection therewith.

At each end of the car a gang-plank 35 is located, being placed diagonally opposite to each other, one at the right and one at the left hand end of the car. These gang-planks are hinged to the bottom of the car in such a manner that they may be folded upward within the car. At such time they stand vertical, as shown by the dotted lines in Fig. 4. The gang-planks are preferably made in longitudinal sections, having hinged connection, whereby the side sections may be folded upon the central sections when the planks are carried upward in the car, and the boards are made in sections also to admit of their adapting themselves to the shape of the runs leading from the pens in which the cattle or stock are confined. The car is also provided with the usual door 36, whereby when a single car is sent to the yard the stock may be entered in the usual manner. The truss-beams located near the door 36 are preferably constructed so that they may be lifted up out of the way when the side openings of the car are used and considerable more head-room is required.

It is to be observed that when the stock is to be loaded or unloaded from the train the end gates may be slid outward through their posts 12 and the posts turned upon their hinges, bringing the gates parallel with the side of the car, as illustrated in Fig. 4, and when the gates are in this position they may be slid on the ways C in the direction of an opposite car until they meet with its gates, thus converting the train into a vestibuled one, and the stock carried from one to the

other over the gang-planks, which extend from one side to the other, as shown in Fig. 4. As the stock is leaving the car, and when a sufficient number has been gathered into one portion of the car, they may be confined to that portion by sliding the adjacent partitions 26 across and locking the sliding partitions in place. The cars are to be connected in vestibule style only while being loaded or unloaded, as when the train is in motion the gates 10 and 11 are applied to close the interior of the cars, and the cars then have the appearance of ordinary stock-cars.

Any one of the tanks 22 will supply sufficient water to the pipe 20 and its branch pipes, being connected when the train is made up to fill all the troughs in the train. Consequently the valves 24, connected with all the tanks but the one being used, are closed. This is done to prevent the water in the troughs from rising too high.

The gang boards or planks are held in their natural position by any approved form of latch. The lower ends of the gates 10 and 11 extend so as to be adapted to bear against the sides of the gang-planks 35 when extended, whereby the said gates are prevented from lateral movement, and any spaces or openings between said planks and gates are thus avoided.

Having thus fully described my invention, what I claim as new and useful, and desire to secure by Letters Patent of the United States, is—

1. A stock-car having at its ends swinging vertical posts, sliding gates supported on said posts and horizontally movable thereon and adapted to form vestibules when extended, and ways on the side of said car for said gates, said parts being combined substantially as described.

2. A stock-car having sliding gates and a rising and falling gang-plank secured to its end, said gates being at the sides and adapted to extend and contact with said gang-planks when the latter are lowered, and thus adapted to form a closed floor, substantially as described.

3. A stock-car having an end sill with one half or portion thereof adapted to receive one end of a gang-plank and another portion having attached thereto one end of a rising and falling folding gang-plank, said parts being combined substantially as described.

4. A stock-car having an end sill with a gang-plank connected with a portion thereof and a portion adapted to sustain the free end of a rising and falling gang-plank on an adjacent car, said gang-planks when lowered forming a floor between said cars, said parts being combined substantially as described.

5. A stock-car having gang-planks at the end, side gates adapted to close the spaces between adjacent cars and having their lower ends adapted to contact with the sides of said gang-planks, and a partition extending across

said car and abutting against a central post thereof, thus forming a chamber in said car, said parts being combined substantially as described.

5 6. A stock-car having sliding partitions movable on side frames of the car and in ways on the floor thereof and posts against which

said partitions are adapted to abut, said parts being combined substantially as described.

CHARLES W. ALLEN.
